ELECTRIC CHIME AND CARRIER FOR THE
VIBRATORY AND STRIKER ELEMENTS
THEREOFLawrence G. Bergeron, Cleveland, Ohio, assignor
of forty-five one-hundredths to S. Eldridge
Sampliner, Euclid, Ohio

Application November 8, 1946, Serial No. 708,716

10 Claims. (Cl. 177—7)

The present invention, while relating particularly as indicated to chimes (resonated bells) such as are adapted for household use, relates in a broader sense to signal or sound producing devices irrespective of the use to which they are put.

I am aware of the fact that signal devices have been heretofore developed in which the striker and vibratory elements thereof are confined within a housing sympathetically tuned with the vibratory element. However, in these prior art devices, the particular mounting for such elements is adapted only for use in conjunction with a particular resonance housing or housings; that is, for example, for either a so-called single or dual or universal purpose device and, therefore, entirely different mountings are required for each different type of device. The aforesaid terms "single purpose," "dual purpose" and "universal purpose" are herein used to respectively designate devices which are capable of emanating a single note, a double note and both a single and double note, said latter type being desirable for example in household installations to enable the tenant or owner to readily determine which of two push buttons have been actuated. Furthermore, in such prior art devices, the resonance chambers associated with vibratory elements of different pitches have been of different lengths whereby the formation of composite units of the dual or universal purpose type has not been feasible.

Accordingly, it is one principal object of this invention to provide a signal device which, in addition to being capable of reinforcing or intensifying the sound produced by a vibratory element, is of such construction that the principal elements thereof, viz., the vibratory and striker elements on an interchangeable carrier can be inserted into any of several forms of resonance housings.

It is another object of this invention to provide a signal device in which the striker and vibratory elements are effectively retained within the resonance housing without the necessity of employing screws, rivets or the like or of performing welding, soldering or like operations.

A further object of this invention is to provide a novel form of carrier on which both the vibratory element and the striker element may be mounted to thus form a simple unitary structure insertable into any appropriate resonance housing.

A still further object of this invention is to provide a novel resonance chamber in the general form of either a tube having a closed end or one having open ends sympathetically tuned with

5 a selected vibratory element by the length and location of an opening along a longitudinally extending side thereof or by the sizes of the openings at the ends thereof, respectively. Such selective tuning makes possible in dual and universal purpose devices the use of resonance housings of equal length, such construction being especially desirable from the standpoints of balanced ornate appearance and manufacturing facility.

10 A still further object of this invention is to provide a novel form of striker mechanism having means for yieldably retaining the striker in a position such that its one end is spaced away from the vibratory element which it is adapted to strike, but that upon movement of said striker away from said vibratory element followed by movement thereof toward said vibratory element, the inertia thereof will cause the same to momentarily move beyond such normal position to strike and 15 bounce away from such vibratory element to thus produce a clear note of substantial intensity.

Other objects and advantages of the invention will become apparent as the following description proceeds.

25 To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In the drawings:

Figs. 1, 2 and 3 are views of a single purpose signal device, Fig. 1 being a central cross section view longitudinally through the resonance housing as indicated by the line 1—1, Fig. 2, and Figs. 2 and 3 being a top plan view of the device illustrated in Fig. 1 and a transverse cross section view taken along line 3—3, Fig. 1, respectively;

40 Figs. 4 and 5 are a central cross section view longitudinally through the resonance housing along line 4—4, Fig. 5, and a top plan view, respectively, of a dual purpose device;

Figs. 6, 7 and 8 are views of a universal purpose signal device, Fig. 6 being a central cross section view longitudinally through the resonance housing and Figs. 7 and 8 being transverse and longitudinal cross section views taken along lines 45 1—1 and 8—8, Fig. 6, respectively; and

Fig. 9 is a perspective view of the unitary removable striker and vibratory assembly illustrated in Figs. 1, 3 and 4.

Referring now to the drawing and first to Figs.

1, 2, 3 and 9, there is shown therein a single purpose signal device comprising three essential elements, viz., a resonance housing 1, a vibratory element 2 and a striker element 3. Housing 1 is herein illustrated as an elongated rectangular tube having open ends and supporting means 4 at the upper end thereof for vertically suspending said housing out of contact with surrounding objects. With regard to the opening 5 at the upper end of housing 1, I have found that by varying the size thereof, it is possible to sympathetically tune the resonance chamber formed by housing 1 with vibrator element 2 without varying the length of said housing. Whatever the scientific foundation for such tuning may be, it has been determined that an increase in the pitch of the vibratory element necessitates an increase in the size of opening 5 in order to effect reinforcement or intensification of the sound emanating from the vibratory element.

The vibratory element 2 and the striker element 3 are each mounted on a single carrier 6 which is slidably fitted into housing 1 and retained therein simply by the friction between said carrier and the inside wall of the housing. Said carrier 6 comprises a channel-like body portion formed with parallel flanges 7 and a bottom connecting portion 8 shaped transversely so as to fit into one of the corners of housing 1, as shown in Fig. 3. At each end of said carrier 6 and adjacent the edges of the flanges 7, there are a plurality of slots 9 which define lugs over which the inwardly extending tension springs 10 may be hooked. The inner end of each spring 10 is formed with a hook engageable in one of the two apertures 11 in vibratory element 2 whereby said vibratory element may be resiliently supported between flanges 7 out of engagement with the carrier proper. Several slots 9 are provided so that any of several different vibratory elements may be mounted thereon with springs 10 being located preferably at or near the nodal points of the vibratory element. The bottom connecting portion 8 of carrier 6 is formed with an opening 13 therethrough for a purpose which will become apparent from the description relating to the other forms of devices illustrated.

Across the space between flanges 7 and parallel to vibratory element 2 is a web plate 12. One convenient manner of securing web 12 in place is to provide openings in carrier 6 into which the projecting lugs 14 of web 12 extend, said web being secured in place by springing the flanges 7 apart, inserting web 12 therebetween with its lugs 14 in register with such openings and then letting the flanges 7 spring together.

Mounted on web 12 is a solenoid 15, surrounding which is a casing 16 having lugs 17 projected through apertures in web 12 and bent over to retain the solenoid in place relative to web 12. Casing 16 is slotted as at 18 so that the solenoid leads, not shown, may project through such slot for convenient connection to a suitable source of electric current. Within solenoid 15 and formed as a part of casing 16 is a tube 19 preferably of brass or like material. The striker element 3 consists at least in part of iron or like magnetizable material and is reciprocable in said tube 19. Striker 3 is yieldably held in its retracted position, as shown in solid lines in Fig. 1, by means of a tension spring 20 having its opposite ends respectively connected to an end cap 21 on tube 19 and to striker 3. A cushioning washer 22 is preferably disposed in cap 21 to prevent objectionable banging of striker 3 against said cap. That end

of striker 3 which is adapted to strike vibratory element 2 is preferably of brass or like material, although it is contemplated that materials such as leather, felt or the like may be employed. The solenoid 15 and striker 3 are so spaced relative to vibratory element 2 that the effect of the magnetic field alone urges the striker to a position with its vibratory element striking and just short of engaging the vibratory element. However, it can now be seen that energization of solenoid 15 will urge striker 3 to the left as viewed in Fig. 1 to the position shown in dotted lines to cause the end thereof to strike the vibratory element and immediately bounce away therefrom and then, upon deenergization of solenoid 15, the tension spring 20 will return the striker to its retracted position. That is to say that the inertia of the striker will carry the same far enough to the left to strike the vibratory element and at the same time the combination of the magnetic field, the spring 20 and the striking impact causes the striker to immediately retract away from the vibratory element even though the solenoid remains energized. This produces maximum amplitude of vibration of the vibratory element and results in a clear strong note which is further amplified by the sympathetically tuned resonance chamber formed by housing 1.

Insofar as the device illustrated in Figs. 4 and 5 is the same as that of Figs. 1, 2 and 3, like reference numerals have been used to designate like parts. The device illustrated in Figs. 4 and 5 is a dual purpose unit and, as shown, comprises two longitudinally contiguous resonance housings 25 and 26 forming a partition wall 27 therebetween. Housings 25 and 26 are of equal length and each is formed with a closed upper end and a longitudinally extending opening 28 and 29, respectively, in its side wall. The length and location of such side wall opening is such as to sympathetically tune each housing with the vibratory element therein. I have found that the length of such side wall opening must be increased as the pitch of the vibratory element therein is increased. It is to be understood that instead of openings 28 and 29 being provided in the side wall of the housings, openings at the top and bottom ends may be substituted, as in the case of the unit illustrated in Figs. 1, 2 and 3.

The carrier assembly with vibratory element 2 and striker element 3 mounted thereon is the same as that illustrated in Figs. 1, 2 and 3 except that striker 3 is provided with an end 30 projected through an opening in cap 21 and through registering openings 13 and 31 in carrier 6 and partition wall 27, respectively, to a point short of engaging vibratory element 2 in housing 26. Vibratory element 2 in housing 26 is resiliently mounted on carrier 6 in a manner similar to that in housing 25 but because a separate striker is not required, the web plate 12 has been omitted. In this case the opening 13 in carrier 6 is in register with opening 29 in housing 26. The normal position of projecting end 30 of the striker is as shown in Fig. 4, but such end is movable by inertia toward the right therefrom to sharply strike the vibratory element 2 in housing 26 by interposing a compression spring 32 between cushioning washer 22 and the bottom wall of cap 21.

It can now be seen that upon energization of solenoid 15 encased within casing 16, the striker element will move toward the left, as viewed in Fig. 4, in opposition to the tension spring 20 to strike vibratory element 2 in housing 25 in the same manner as previously described in relation

to Fig. 1. Then, upon deenergization of solenoid 15, the tension spring 20 will cause said striker element to move toward the right, whereupon the inertia thereof will compress spring 32 so that the projecting end 30 of the striker will sharply strike the vibratory element 2 in housing 26 and immediately upon so striking the vibratory element, the compression spring 32, together with the impact of the striking, will cause said end 30 to be forced back to the normal position shown in Fig. 4. Thus it can be seen that successive energization and deenergization of solenoid 15 effects a two-note bing bong signal. With an ordinary push button, the time interval between such successive notes is, of course, dependent upon the length of time that the solenoid 15 is kept energized, but, of course, a predetermined time interval between such notes can be accomplished, for example, by employing a push button which closes the electric circuit only momentarily and then trips to open the circuit, even though the operator retains the push button in a depressed position.

The so-called universal purpose signal device illustrated in Figs. 6, 7 and 8 is substantially the same as the dual-purpose device illustrated in Figs. 4 and 5. The only different feature of this universal purpose device is that the web plate 33 in carrier 6 has mounted thereon two striker elements and two solenoids, whereby successive energization and deenergization of one solenoid effects a two-note signal, as in the case of the dual purpose unit illustrated in Figs. 4 and 5 and energization of the other solenoid effects a single note signal. Thus, the solenoids may be wired to push buttons disposed, for example, at the front and rear doors, respectively, of a home and because of the difference in the signals, the tenant or owner can readily ascertain which push button was actuated.

While in the accompanying drawings the resonance housings are shown as being of sheet metal, it is to be understood that the same may be made from extruded tubing or, if desired, be fabricated of wood or like material in order to vary the tonal quality of the signal. However, regardless of the materials used in making the housings, it can be seen that once the sizes and lengths thereof are standardized, a single universal carrier 6, on which both the vibratory element 2 and the striker element or elements 3 are capable of being mounted, can be used in a wide variety of combinations, as for example the three variations illustrated, whereby a suitable web plate with the proper striker and solenoid assembly thereon can be readily mounted thereon and simply slipped into the housing. Likewise, as shown in Figs. 4 and 6, the web plate may be omitted altogether and only a vibratory element 2 mounted onto the carrier 6. To summarize, it can be seen that there is but one standard carrier 6 and two different web plates, one of which has a single or double-ended striker element thereon and the other of which has both a single-ended and a double-ended striker element thereon, all of the other parts such as the tension springs 10, solenoids 15, casings 16, etc. being identical.

Other modes of applying the principle of the invention may be employed, change being made as regards the details described, provided the features stated in any of the following claims or the equivalent of such be employed.

I therefore particularly point out and distinctly claim as my invention:

1. A device of the character described, comprising a vibratory element, a resonance housing

thereabout, a striker element for effecting vibration of said vibratory element, and a carrier in said housing on which both of said elements are mounted, said carrier being formed with flanges yieldably engaging said housing for thus frictionally retaining said carrier in said housing.

2. A device of the character described, comprising a pair of longitudinally contiguous resonance housings, a vibratory element in each housing, separate carriers in each housing on which said vibratory elements are mounted, and a striker element between said vibratory elements adapted to be moved in opposite directions to alternately strike said vibratory elements, said striker element being supported by one of said carriers.

3. A device of the character described, comprising a pair of longitudinally contiguous resonance housings, a vibratory element in each housing, separate carriers in each housing on which said vibratory elements are mounted, the mounting of said vibratory elements being at the nodal points adjacent each end thereof, a striker element between said vibratory elements adapted to be moved in opposite directions to alternately strike said vibratory elements at points intermediate the nodal points thereof, and another striker element adapted to be moved to strike but one of said vibratory elements at a point between one of the nodal points and the adjacent end thereof, both of said striker elements being supported by one of said carriers.

4. A device of the character described, comprising a pair of longitudinally contiguous resonance housings, a vibratory element in each housing, separate carriers in each housing on which said vibratory elements are mounted, a solenoid mounted on one of said carriers, and a striker element at least in part of magnetizable material within said solenoid and yieldably held in a position with one of its ends adjacent one of said vibratory elements, said striker being movable upon successive energization and deenergization of said solenoid to successively strike said vibratory elements.

5. A device of the character described, comprising a pair of longitudinally contiguous resonance housings, a vibratory element in each housing, separate carriers in each housing on which said vibratory elements are mounted, the mounting of said vibratory elements being at the nodal points adjacent each end thereof, two solenoids mounted on one of said carriers, and a striker element at least in part of magnetizable material within each solenoid, each striker element having one end thereof yieldably retained remotely spaced from one of said vibratory elements, and one of said striker elements having the other end thereof closely adjacent the other of said vibratory elements whereby successive energization and deenergization of one of said solenoids effects movement of the latter striker element to successively strike both of said vibratory elements, and successive energization and deenergization of the other of said solenoids effects movement of the other striker element to strike but one of said vibratory elements, the ends of said one of said striker elements striking said vibratory elements at points intermediate the nodal points thereof and said other striker element striking one of said vibratory elements at a point between one of the nodal points and the adjacent end thereof.

6. A striker and vibratory element assembly for a device of the character described, comprising a channel-like body formed with spaced flanges and a longitudinally extending web transversely between such flanges, a vibratory element mounted

between such flanges, and a striker carried by such web adapted to be moved so as to strike said vibratory element.

7. A striker and vibratory element assembly for a device of the character described, comprising a channel-like body formed with spaced flanges, a bottom connecting portion, and a longitudinally extending web transversely between such flanges, a vibratory element mounted between such flanges, and a striker carried by such web adapted to be moved so as to strike said vibratory element, said striker having an end thereof projecting through an opening in the bottom connecting portion of said body.

8. A striker and vibratory element assembly for a device of the character described, comprising a channel-like body formed with spaced flanges, a bottom connecting portion, and a longitudinally extending web transversely between such flanges, a vibratory element mounted between such flanges, and two strikers carried by such web each adapted to be moved so as to strike said vibratory element, one of said strikers having an end thereof projecting through an opening in the bottom connecting portion of said body.

9. A striker and vibratory element carrier for a device of the character described, comprising a channel-like body formed with spaced flanges including a plurality of openings therethrough, and a web disposed transversely between such flanges

formed with projecting lugs thereon fitted into such flange openings.

10. A device of the character described, comprising a pair of hollow elongated resonance housings of the same length each formed with a closed upper end and an open lower end and an opening in its side wall, vibratory elements in each of said housings capable of emitting notes of different pitch, and striker means for effecting vibration of said vibratory elements, the side wall opening in the housing associated with the vibratory element of higher pitch being larger than that in the housing associated with the other vibratory element whereby the resonance chambers formed by said housings are sympathetically tuned with the vibratory elements therein.
